UNITED STATES PATENT OFFICE

JEREMIAH C. DOUGHERTY, OF CHICAGO, ILLINOIS

MATCH SAFE

Application filed February 17, 1928. Serial No. 254,989.

The invention relates to improvements in match safes and has for its object the provision of an improved construction of this character adapted and arranged to contain 5 a supply of matches for delivering said matches singly for use.

Another object of the invention is the provision of a match safe of this character which is of simple construction and highly efficient 10 in use.

Another object of the invention is the provision of a match safe provided with improved means for delivering the matches.

Another object of the invention is the provision of a match safe equipped with improved means for taking care of the burnt 15 matches.

Other objects will appear hereinafter.

The invention consists in the combination 20 and arrangements of parts hereinafter described and claimed.

The invention will be best understood by reference to the accompanying drawings forming a part of this specification and in 25 which—

Fig. 1 is a perspective view of a match safe embodying the invention, portions thereof being broken away and shown in section for the sake of clearness;

Fig. 2 a perspective view of a modified 30 form of construction; and

Fig. 3 a section taken substantially on line 3—3 of Fig. 2.

The form of construction illustrated in 35 Fig. 1 comprises a rectangular receptacle 5 having a downwardly and forwardly sloping bottom 6 leading to a discharge opening 7 formed at the lower end of the front wall of the receptacle as shown. A match tray 8 is

40 arranged at the lower end of the front wall of the receptacle 5, said match tray being transversely concave in cross-section and sloping upwardly from the bottom of the discharge opening 7, as shown, said tray thus 45 constituting substantially an upwardly extending continuation of the bottom 6 of the receptacle. A stop ledge 9 is arranged transversely in the tray 8 just outside of the discharge opening 7, the inner side 10 of said 50 ledge gradually sloping upwardly, as shown,

and the outer side 11 thereof being abrupt and re-entrant in form. By this arrangement the matches in the receptacle 5 will be caused to feed downwardly along the inclined bottom 6 and present themselves singly in the discharge opening 7, being held from free flowing or passage out of said discharge opening by the upward slope 10 of the stop ledge 9 and whereby the lowermost match in the receptacle will always be presented for ready 55 removal. In case one of the matches becomes displaced or is dropped into the tray 8, said match will normally roll down in said tray until it rests against the ledge 11 thereby being prevented from rolling back to interfere with the lowermost match of the receptacle presented for removal, from which position said displaced match may be also 60 readily removed for use. The transversely concave form of the tray tends to assist in return of dropped matches to position against the ledge 9 and also tends to facilitate removal of said dropped matches, as will be 65 readily understood.

A finger notch 12 is provided in the lower 70 central portion of the front wall of the receptacle 5 and a finger opening 13 is provided thereunder in the bottom 6, thereby greatly facilitating the removal of matches 75 through the opening 7.

The receptacle 5 is provided with a removable cover 14 having a depending burnt match tray 15 at its forward edge and a match box stand 16 on the central portion thereof, as shown. By this arrangement provision is 80 made for the care of the burnt or used matches and also provision is made for the use of a box of the so-called safety matches when desired.

In the modified form of construction illustrated in Figs. 2 and 3, the match tray 8' is made flat or horizontal in form and the burnt match tray 15' is formed on the top of the cover 14 as indicated. Otherwise the construction is the same as that already described, 85 except for a slight difference in shape.

While I have illustrated and described the preferred form of construction, this is capable of variations and modifications without departing from the spirit of the invention. I, 90 100

therefore, do not wish to be limited to the precise details set forth, but desire to avail myself of such variations and modifications as fall within the scope of the appended 5 claims.

I claim:

1. A match safe comprising a receptacle having an inclined bottom, there being a discharge opening in the front of said receptacle 10 at the lower end of said bottom; a match supporting tray projecting from the lower front portion of said receptacle and forming substantially a continuation of said bottom; and a transverse stop ledge in said tray just outside of said discharge opening and stopping short of the top of the side walls of said tray. 15
2. A match safe comprising a receptacle having an inclined bottom, there being a discharge opening at the front of said receptacle 20 at the lower end of said bottom and a finger opening in the bottom of said receptacle immediately below the central portion of said discharge opening; a match supporting tray projecting from the lower front portion of 25 said receptacle and forming substantially a continuation of said bottom; and a transverse stop ledge in said tray just outside of said discharge opening. 30
3. A match safe comprising a receptacle having an inclined bottom, there being a discharge opening in the front of said receptacle at the lower end of said bottom and a finger opening in the bottom of said receptacle immediately below the central portion of said 35 discharge opening; a match supporting tray projecting from the lower front portion of said receptacle and forming substantially a continuation of said bottom; and a transverse stop ledge in said tray just outside of said 40 discharge opening, the inner side of said ledge sloping gradually and the outer side being abrupt. 45
4. A match safe comprising a receptacle having an inclined bottom, there being a discharge opening in the front of said receptacle at the lower end of said bottom; a match supporting tray projecting from the lower front portion of said receptacle and forming substantially a continuation of said bottom, said 50 tray being transversely convex in form and sloping upwardly from the bottom of said discharge opening; and a transverse stop ledge in said tray just outside of said discharge opening. 55
5. A match safe comprising a receptacle having an inclined bottom, there being a discharge opening in the front of said receptacle at the lower end of said bottom, a match supporting tray projecting from the lower front 60 portion of said receptacle and forming substantially a continuation of said bottom, said tray sloping upwardly from the bottom of said discharge opening, and a transverse stop ledge in said tray just outside of said discharge opening, the inner side of said ledge 65 sloping gradually and the outer side being abrupt. 70

In testimony whereof I affix my signature at 10 South La Salle Street, Chicago, Illinois.

JEREMIAH C. DOUGHERTY.
